No. 811,275.

PATENTED JAN. 30, 1906.

J. P. COLE.
DREDGING APPARATUS.
APPLICATION FILED MAY 26, 1905

UNITED STATES PATENT OFFICE.

JAMES P. COLE, OF CHICAGO, ILLINOIS.

DREDGING APPARATUS.

No. 811,275.

Specification of Letters Patent.

Patented Jan. 30, 1906.

Application filed May 26, 1905. Serial No. 262,314.

To all whom it may concern:

Be it known that I, JAMES P. COLE, a resident of Chicago, in the county of Cook and State of Illinois, have invented certain new and useful Improvements in Dredging Apparatus, of which the following is a full, clear, and exact description.

The invention relates to dredging apparatus, and more particularly to apparatus for raising submerged deposit—*e. g.*, sand, gravel, or granulated mineral matter.

The invention designs to provide improved apparatus in which air from a jet is commingled with the gangue to supplement a water-jet for lifting the gangue. In practice it has been found in apparatus heretofore constructed that when the air was not thoroughly intermixed with the water from the lifting-jet before entering the gangue the result was an alternate flow of air and water or gangue rather than an evenly-intermixed flux of the air and water bearing the detritus in suspension.

The invention further designs to increase the efficiency of apparatus of this type by providing means whereby the water and air are thoroughly and evenly intermixed or mechanically combined so even and constant pressure and flow of the gangue will result.

The invention further designs to provide several improvements in dredging apparatus.

The invention consists in the several novel features hereinafter set forth and more particularly defined by claims at the conclusion hereof.

In the drawings, Figure 1 is a side elevation of an improved apparatus embodying the invention, parts being broken away and shown in section. Fig. 2 is a vertical central section of the jet-head at the lower end of the gangue-tube, taken on line 2 2 of Fig. 1. Fig. 3 is a vertical section on line 3 3 of Fig. 2. Fig. 4 is a horizontal section on line 4 4 of Fig. 2. Fig. 5 is a section on line 5 5 of Fig. 2. Fig. 6 is a vertical section on line 6 6 of Fig. 4. Fig. 7 is a horizontal section on line 7 7 of Fig. 1.

The gangue-tube 10, which may be of any desired length, may be suspended or supported in any suitable manner as well understood in the art. To the lower end of the gangue-tube is secured a dredging-head 11 with a central chamber 12 in its upper portion, which is in communication with the lower end of the gangue-tube. Intake-ducts 13 in suitable number radiate from chamber

12 and are open at their outer ends to receive the gangue. Lugs 14 project from the head at each side of the intakes 13 to support a grid 15, formed of rods extending across the mouth of each intake to prevent obstruction of the gangue-passage by solids too large in size. The gangue projected upwardly through the gangue-tube passes by gangue tube or pipe 16 to any desired point. 65

A pipe 18, connected to a suitable source of supply—*e. g.*, a pressure-pump—supplies water under pressure to a duct 18', formed in the head 11, the lower end of which duct is extended horizontally at 18^a to conduct water 70 under pressure to a nozzle 18^b, from which water is projected into the gangue-tube. A pipe 17 supplies air under pressure from a suitable source to a duct 17' in head 11, and said duct has its lower end extended horizontally, as at 17^a, to conduct air into nozzle 17^b, from which air is projected into nozzle 18^b. The air-jet thus discharges into the water-jet, where the air and water are thoroughly commingled in transit to the gangue-tube. The chamber in nozzle 18^b, surrounding the air-jet, serves as a mixing-chamber for the air and water. Resultantly the evenly-mixed discharge from nozzle 18^b is a medium whereby the gangue will be raised 80 and whereby a uniform flow of the gangue is attained. By thus mechanically combining the water and air there is no material tendency of the air to expand downwardly through the intakes of the gangue-tube; but, on the contrary, the expansion of air is gradual in transit through the gangue-tube, and thus the maximum energy and efficiency of the air is obtained. The pipes 17 and 18 are separately controlled by valves 95 17^c and 18^c, respectively, located at any convenient point, and thereby proper relative discharge of air and water can be maintained, the purpose of such regulation being to establish equilibrium between the air and water, which will result in constant and even flow of the mixture for lifting the gangue. Furthermore, in practice the desideratum is to avoid excess of water, which by reason of its greater specific gravity will retard the flow 105 of the gangue, while an excess of air will cause irregular flow and loss of expansive energy. Manifestly from the foregoing it will be seen that the air and water are mechanically combined or commingled before or approximately at the time of discharge into the gangue-tube and balance of the air and water 110

110

columns to effect proper proportionate discharge of the lifting medium into the gangue-tube can be regulated to a nicety. It will be understood that any suitable means may be employed for providing the fluids under suitable pressure—*e. g.*, seventy-five to three hundred pounds.

The lower end of head 11 is tapered to facilitate penetration into a deposit, and a pilot-jet 19 is disposed to discharge centrally at the lower end of the head. The pilot-jet serves to direct descent of the gangue-tube and laterally displace the deposit beneath the gangue. The pilot-jet communicates with a duct 19^a, to the upper end of which is connected pipe 19^b, connected to the source of water-supply under pressure. A valve 19^c controls the operation of the pilot-jet, so it can be rendered operative and inoperative when desired. The head is also provided with a series of cutter-jets 20, from which water can be projected laterally to loosen and displace the deposits at the side of the head. The jets 20 in any suitable number communicate with an annular chamber 20', to which water under pressure is supplied through a duct 20^a in head 11 and a pipe 20^b also connected to the source of water-supply under pressure. A valve 20^c controls the operation of the cutter-jets and may be located at any desired point. The water-pipes for the lifting-jet, the pilot-jet, and the cutter-jet and the pipe for the air-jet are arranged around the gangue-tube. A tubular jacket 22, secured to the upper end of the head by ring 23 and bolts 24 inclose the several pipes. The gangue-tube and jacket are also secured together at their upper ends by a ring 25 of any suitable construction.

The operation of the improved apparatus will be as follows: When the gangue-tube and dredging-head have been lowered to work in the submerged deposit, the pilot-jet loosens and displaces the deposit, tending to cut a downward path for the apparatus. The cutter-jet supplements the action of the pilot-jet and loosens and displaces the surrounding deposits, so they will be drawn into intakes 13 when the lifting-jet and air-jet are in operation. The air discharged from nozzle 17^b under pressure commingles with the water in the nozzle of the lifting-jet 18^b, and the mixture is projected upwardly in the gangue-tube to force the gangue which has been drawn through the intakes. The mixture of the water and air being effected prior to discharge thereof into the gangue-tube, the lifting medium is rendered uniform and evenly expansive, resulting in effective, even, and constant upper projection of the gangue.

The invention is not to be understood as restricted to the details of construction set forth, but may be modified by the skilled mechanician without departing from the spirit and scope of the invention.

Having thus described the invention, what I claim as new, and desire to secure by Letters Patent, is—

1. In dredging apparatus, the combination of a gangue tube, or duct, an air-jet and a water-jet, said jets discharging their respective fluids so they will commingle before the fluids are discharged into the gangue-duct. 70

2. In dredging apparatus, the combination of a gangue tube or duct, an air-jet and a water-jet, and comprising a mixing-chamber wherein the fluids from said jets are combined prior to the discharge into the gangue-duct. 75

3. In dredging apparatus, the combination of a gangue tube or duct, an air-jet and a water-jet, said air-jet discharging its fluid into the water stream so the fluids will be mechanically combined before discharge thereof 85 into the gangue-duct. 80

4. In dredging apparatus, the combination of a gangue tube or duct, a head at the lower end of said tube or duct and provided with intakes, an air-jet in said head, and a water-jet in said head, said air-jet discharging into the water column so the fluids will be combined prior to being discharged under pressure into the gangue-duct. 90

5. In dredging apparatus, the combination of a gangue tube or duct, a duct for water, and an upwardly - extending nozzle through which water from said duct is forced, and an air-jet discharging into said nozzle. 95

6. In dredging apparatus, the combination of a gangue-tube, a lifting-jet, an air-jet, a head at the lower end of said gangue-tube, and a centrally - arranged downwardly-discharging pilot-jet at the lower end of said head. 100

7. In dredging apparatus, the combination of a gangue-tube, a head at the lower end of said gangue - tube, a centrally - arranged, downwardly-discharging pilot-jet at the lower end of said head, a water-jet discharging into the gangue-duct, and an air-jet discharging into said water-jet. 110

8. In dredging apparatus, the combination of a gangue-tube, a head at the lower end of said gangue-tube, a centrally-arranged downwardly - discharging pilot - jet at the lower end of said head, a water-jet discharging into the gangue-duct, and an air-jet discharging its fluid to commingle with the water passing through the water - jet so the fluids will commingle before discharge into the gangue-duct. 115

9. In dredging apparatus, the combination of a gangue tube or duct, a head at the lower end of the gangue-tube and having a chamber in its upper portion in communication with the gangue-tube, water and air jets for supplying fluids to force the gangues upwardly in the tube, and a pilot-jet at the lower end of said head, and a duct in said 125 130

head disposed at the side of said gangue-duct and communicating with the pilot-jet.

10. In dredging apparatus, the combination of a gangue-tube, a head at the lower end of said tube, a chamber near the lower end of said head, a pipe or duct for supplying water under pressure to said chamber, one or more cutter-jets leading outwardly from said chamber and water and air jets for forcing 5 the gangue upwardly in the tube.

11. In dredging apparatus, the combination of a gangue-tube, a head at the lower end of said tube, a chamber near the lower end of said head, a pipe or duct for supplying 15 water under pressure to said chamber, one or more cutter-jets leading outwardly from said chamber, water and air jets for forcing the gangue upwardly in the tube, and a centrally-disposed downwardly-discharging pilot-jet at 20 the lower end of the head.

12. In dredging apparatus, the combination of a gangue-tube, a head at the lower end of said tube, a chamber near the lower end of said head, a pipe or duct for supplying 25 water under pressure to said chamber, one or more cutter-jets leading outwardly from said chamber, water and air jets for forcing the gangue upwardly in the tube, a downwardly-discharging pilot-jet, and a separate duct 30 leading to the pilot-jet.

13. In dredging apparatus, the combina-

tion of a gangue-tube, a head at the lower end of said tube, intakes in said head, a gangue-duct in said head, a water-jet and an air-jet, both discharging their fluids so they 35 will commingle prior to discharge into the gangue-duct, the discharge of the mixed fluid being centrally arranged in the duct.

14. In dredging apparatus, the combination of a gangue-tube, a water-jet and an air-jet for forcing the gangue upwardly a separate pilot-jet, and valves whereby the lifting-jets and the pilot-jet can be separately controlled. 40

15. In dredging apparatus, the combination of a gangue-tube, a water-jet and an air-jet for forcing the gangue upwardly, a cutter-jet, and means whereby the operation of said jets can be controlled so the lifting-jets and the cutter-jet can be independently or simultaneously operated. 45

16. In dredging apparatus, the combination of a gangue-tube, a water-jet and an air-jet, for forcing the gangue upwardly, a cutter-jet, a pilot-jet, and means whereby the operation of the pilot-jet, lifting-jets and cutter-jet, can be separately controlled. 50 55
